Attn: Mrs. E.

United States Patent Office.

G. F. WHITE, OF AURORA, OREGON.

Letters Patent No. 93,148, dated July 27, 1869.

IMPROVEMENT IN SHINGLE-MACHINE.

The Schedule referred to in these Letters Patent and making part of the same.

To all whom it may concern.

Be it known that I, G. F. WHITE, of Aurora, in the county of Marion, and State of Oregon, have invented a new and useful Machine for Making Shingles; and I do hereby declare that the following is a full and exact description thereof, reference being had to the accompanying drawings, making part of this specification, in which—

Figure 1 is a plan or top view of my machine, with a portion of the platform removed, to show parts that would otherwise be hidden.

Figures 2 and 3 are elevations, each on that side of the plan, fig. 1, to which it is contiguous.

The other figures exhibit parts in detail, and will be more particularly referred to hereafter.

In all the figures, like parts are indicated by the same letters of reference.

The nature of my invention consists in so arranging the parts of the apparatus, to be hereinafter described, as that the operation of splitting the shingles from the block or bolt may be immediately followed by that of gauging them to a proper width, and smoothing their surfaces, while giving these, at the same time, the proper angle of convergence, and preserving uniformity of thickness in all the shingles.

A A are the sills, posts, and girders constituting the frame of my machine.

B is the main driving-shaft, furnished with fast and loose pulleys, B' B'', by which its motion may be derived from any power, or it may be allowed to rest, and giving motion, by fixed pulleys and belts, to the other parts of the machine.

C is a vertical shaft, having its step in the lower part of the frame A, and its upper end supported in a bearing fixed in the frame of the bolt-holder, (to be hereafter referred to.) It is provided with a pulley, a, and is driven by a belt from the main driving-shaft.

Securely fixed at the upper end of the shaft C, and revolving with it, is the river or splitter, composed of a wooden or metallic rim, D, (see Figures 1, 2, 4, 5,) which holds, between itself and the hub, the riving knives b b.

These may be two or more in number, and are secured with their edges radial to the rim. Their upper and under surfaces form a spiral plate around the axis, like a post-auger blade, each plate terminating radially immediately under the edge of the knife attached to the next plate, so that the space of the thickness required for a shingle is open between each knife-edge and the plate of its neighbor.

That portion of the plate which is under a knife-edge is free from contact with the rim and hub for a portion of the distance around from its lower edge to its knife, as seen at b' b', figs. 4 and 5, which are a di-

rect and an oblique view of the under side of the river, to allow it a slight degree of flexibility, which is governed and regulated by the pressure of the spring e, attached to the under side of the rim, and bearing against the under side of the free end of the plate, as shown.

Boxes, d d, are formed in the construction of the frame, to serve as bolt-holders, and the river is so placed on the shaft C as that its knives shall come in contact with and split from the bottom of the bolts or blocks placed in the boxes d.

E E are the shafts of the pairs of saws e e', driven in opposite directions by belts from the main shaft B, as shown by arrows in fig. 2.

As each of these pairs of saws is a duplicate of the other in construction and operation, it is only necessary to describe one and its adjuncts.

The bearings of the shaft E are so placed that the edges of the saws project a slight distance above the surface of the bed or platform A', partially covering the top of the frame A, as seen in fig. 1, where the dotted lines indicate that portion which has been removed to make the drawing clear.

The saw e is fixed to a collar sliding by a groove and spline on the shaft E, so as to revolve with it, and is moved toward or from the saw e', which rotates in a constant plane by the slipper f, of the kind commonly used, and plainly shown in the drawing.

A rest, g, seen detached in Figures 9 and 10, slides on the guide-bars h h, between the saws, and in a direction at right angles with their axis, against which the shingles are laid, and pushed between the saws, to be cut by them to the required width.

The rest g is drawn back for another shingle by means of a cord attached to the barrel i, containing a spring, i, shown in blue lines in fig. 9, which last is kept in tension by the common device of a ratchet and pawl, k.

F is a vertical shaft, driven by a belt from the main shaft C, and carrying a planer, for smoothing the shingles, and giving them the necessary taper.

This planer is composed of two plates, G G', firmly fixed one above the other on the shaft F, so as to turn with it, with a sufficient distance between them to allow for adjustment of the plane-bits or knives.

Figure 6 is a separate view of the top face of the upper plate G and the bottom face of the lower plate G';

Figure 7 is a view of the contiguous faces of the same plates; and

Figure 8 is an edge view and partial section of the same.

The upper plate G, it will be seen, is slightly coni-

cal on its under surface, and the plane-bits or knives *l l* are adjustable, so that their edges may be either parallel with the radii of the surface or describe a more acute or obtuse cone.

Rollers *m m* are set in the under face of the plate *G*, in close proximity to the edges of the knives, and are also adjustable, to be parallel with them.

The degree of inclination of the knives of the plate *G* to the plane of rotation determines the taper of the shingle.

The knives and rollers of the lower plate *G'* are similar in construction and arrangement to those of plate *G*, but are so set as to revolve in the same plane with the upper surface of the platform *A*.

Opposite to each pair of saws, and on each side of the planer, is a feeder, revolving horizontally on the vertical shaft *H*, and driven by a belt from the main driving-shaft *B*.

This feeder is composed of two plates, *I K*, one of which, *I*, is fixed on the shaft, with its upper surface flush with the platform *A'*, and the other, *K*, is loose on the hub of the plate *I*, so as to be free to assume a position out of a horizontal plane. It is made to turn with the shaft, however, by means of the pins *n n*, projecting upward from the plate *I*, through holes in the plate *K*.

The upward motion of plate *K* is limited by the heads of the pins *n n*.

L L are two friction-rollers, attached to stems, which are free to slide vertically in the sockets *o o*, through which they pass, until they come in contact with and are held down by the springs *M M*.

These rollers impose on the top of the plate *K*, near the edge which is next to the planer *G G'*, and by the springs *M*, grip and hold the shingle firmly by one end between the plates *I K*, while it is being planed.

A bar, *N*, which may have elasticity to act as a spring, when desirable, is attached by one end to a convenient point on the frame *A*, and has its other end projecting into the space between the plates *I* and *K*, for the double purpose of keeping the space open for the ready introduction of a shingle from the saws, and for throwing out the shingle when it has been planed, and is left free by being relieved from the pressure on the plate *K*.

It will be seen from the drawings that the speed of the planer is much greater than that of the feeder, so that while the shingle is being carried from the saws around to the point where it is released, the plane-bits perform their office in tapering and smoothing effectually.

The operation of my machine is as follows, viz:

The blades of the river having been put in proper condition, the saw *e*, set upon the shaft *B* by the shipper *f*, and secured at the proper distance from the saw *e*, and the knives and the rollers of the planer properly adjusted, bolts or blocks are put into the boxes *d d*, and the machine put in motion.

As fast as the shingles are split, they fall on the platform *A'*, and are conveyed to the rest *g*, placed in front of it, and pushed between the saws, which gauge them to the required width, when their ends are immediately seized by the feeder *I K*, (the rest returning for another shingle,) and held while the planer *G G'* smooths and tapers them, as described, when they are thrown out by the bar *N*, to be bundled or otherwise disposed of.

Having thus fully described my invention,

What I claim as new therein, and desire to secure by Letters Patent, is—

1. The river, consisting of the rim *D*, knives *b b*, plates *b'*, and springs *c*, together with the adjustable gauge-saws *e e'* and the self-retracting rest *g*, all arranged substantially as described, and operating as and for the purpose set forth.

2. The feeder, composed of the plates *I K*, rollers *L*, springs *M*, or their equivalent, and bar *N*, arranged and operating substantially as described.

3. The rotating planer *G G'*, with its adjustable knives *l* and rollers *m*, in combination with the feeder *I K L M N*, as hereinbefore specified, for the purpose set forth.

4. The combination of the width-gauging devices *e e'* *g*, with the feeder above mentioned, substantially as set forth, and for the purpose described.

G. F. WHITE.
